TOOLBOX

Theresa Fuhse, Bradley Beach, N. J.

Application September 6, 1950, Serial No. 183,368

4 Claims. (Cl. 112—218)

1

This invention relates to a tool box for workers in the needle trade.

Mass production in the needle trade requires a number of bobbins readily available for the sewing machine operators. In many plants, changing the thread occurs often, at times within minutes, in order that the color of the thread can be matched to the color of the garment under construction. At times there may be as many as fifteen to seventeen shades in one bundle.

It is an object of the instant invention to provide a tool box in which the bobbins are organized and within easy sight and reach, and yet definitely out of the way.

A further object is to provide a tool box in which the bobbins are prevented from slipping off the work-bench.

Another object is to provide a tool box that can be carried in the pocket.

Other objects of the instant invention will become apparent in the course of the following specification.

In the attainment of these objectives, the tool box is especially designed to fasten easily and temporarily into the small and seldom used space on the work-bench adjacent the neck of the sewing machine and bobbin winder. The interior of the box is divided into five rows, the two outside and center rows being designed to hold the bobbins while intermediate two adjacent rows is a space for a bobbin case. An extension on the box at the front provides a means for removably attaching the box into the groove created when the machine is fitted into the work-bench. A cover is removably inserted over the box and a tray equipped with a pair of scissors and a screwdriver may be removably inserted in the cover.

The invention will appear more clearly when taken in conjunction with the drawings showing by way of illustration a preferred embodiment of the inventive idea.

In the drawings:

Figure 1 is a top plan view of the tool box constructed in accordance with the principles of this invention;

Figure 2 is an end view of the tool box shown in Figure 1;

Figure 3 is a front view of the tool box shown in Figure 1;

Figure 4 is a plan view of the tool box with the cover removed;

Figure 5 is a sectional view along 5—5 of Figure 4;

Figure 6 is a transverse cross sectional view of the box as shown in Figure 3;

Figure 7 is a front view of the fastener removably securing the box to the work-bench;

Figure 8 is a side view of the fastener shown in Figure 7;

2

Figure 9 is a top plan view of the interior of the tray removably inserted in the cover; and

Figure 10 is a perspective view of the tool box attached to the work-bench adjacent the bobbin winder and the neck of the sewing machine.

Referring now in greater detail to the drawings where like reference numerals indicate like parts, reference numeral 10 indicates the tool box.

10 The tool box 10 may be formed from any suitable material, such as plastic, and is constituted of the front member 11 (Fig. 2) spaced parallel from the back member 12, and the spaced end members 13 and 14, the corner 15 (Fig. 1) of the end member 13 being of arcuate form as illustrated for fitting around the neck 62 of the sewing machine (Fig. 10). Each of the spaced members is extended upwardly substantially to the top of the later mentioned bobbins 23 when inserted. A bottom member 16 is disposed over the corresponding edges of the other members and has an integrally formed rearwardly extended portion 17 which fits under the bobbin winder wheel and against the bobbin winder base to aid in keeping the box in place and to prevent interference with the bobbin winder wheel or power belt.

Disposed between the front and back members 11 and 12 are the spaced parallel partitions 18, 19, 20, and 21, the partition 21 adjacent the end member 13 terminating interiorly of the front member 11. Coacting with the partition 21 is the partition 22 at 90° thereto. It will be noted in Figure 5 that all the partitions are extended upwardly only a short distance relative to the known bobbins 23 which construction together with the space provided between the rows is designed to facilitate the removal of the bobbins.

40 Extended forwardly of the box 10 are two spaced parallel projections 24 and 25 which are attached to the outer surface of the front member 11 by any suitable means or are integrally formed therewith. Through the projections are

45 two aligned and threaded holes through which the externally threaded rod 26 is adjustably inserted. Intermediate the ends of the rod 26 is an opening 27 (Fig. 4) through which the fastener 28 is removably inserted for coaction with a groove 63 formed around the periphery of the opening made in the work-bench for the insertion of the base of the machine when said base is fitted therein. By making the rod 26 longitudinally adjustable, the position of the opening 27 can be varied in accordance with any variations of the spacing of the groove from the neck of the machine from machine to machine.

Over the open top of the box 10 is the removable cover member 29 having spaced parallel

front and back members 11a and 12a, spaced parallel end members 13a and 14a, and a top member 30, integrally formed along corresponding edges and coacting with corresponding members of the box 10 in as far as the front and back and end members are concerned, the cover member being removably slip fitted over the outer surfaces of the corresponding members of the box. It will be noted that the cover member 29 has an extension 31 at the front which is designed to 10 removably cover the previously described projections 24 and 25 and threaded rod 26 when the cover is in place.

If desired, a tray 32 may be removably inserted near the top member 30 of the cover member 29. The tray is constituted of a floor member 33, spaced parallel front and back members 34 and 35, and spaced parallel end members 36 and 37 integrally formed or otherwise fastened along corresponding edges as in the other constructions and coacting with the inner surfaces of corresponding members of the cover member 29 in which it is removably inserted. To maintain the tray 32 in position, the inner surface of the front member 11a of the cover member may have a vertical slideway 48 in which a retractile guide 49 slides while a protrusion 50 on the back member 12a of the cover further aids in holding the tray in position. On the inner surface of the floor member 33 of the tray are any suitable fasteners 40, 41, and 42 (Fig. 9) for the removable attachment of a pair of scissors as illustrated and on either side of which may be the finger grip recesses 43 and 44, the recesses aiding the removal of the tray. On the same surface of the tray with the scissors may be a catch for coacting with a réceptacle 45a for removably holding the screwdriver 46.

In operation:

The sewing machine operator with the bobbins 23 in the compartments, together with the bobbin case 47 adjacent the arcuate corner, may have available some eighteen bobbins or sixteen bobbins and a thimble and tailor's chalk and needles, and, if the tray 32 be used, may also have available a pair of scissors and a screwdriver. With the cover member 32 removed, the box 10 is inserted between the small space on the work-bench adjacent the neck of the sewing machine and the bobbin winder 64 and within easy reach of the worker's hand. The split fastener 28, first passed through the rod 26, is then inserted in the groove 63 where the machine fits into the work-bench making any necessary longitudinal adjustments with the rod to properly position the fastener relative to the groove. With the extended portion 11 of the bottom member 16 of the box fitted under the bobbin winder wheel and abutting the bobbin winder base, the box 10 is secured against the constant vibration of the work-bench when the machines are running and prevents the bobbins from spilling and rolling off. The fastener 28 may be carried in the box 10 when not in use.

Of course, the bottom of the box may be provided with an anti-friction surface such as rubber and it will be understood that the invention is not limited to the exact disclosure herein described but may lend itself to a variety of expressions within the scope of the appended claims.

What is claimed is:

1. A tool box in combination with a sewing machine and a bobbin winder and a work-bench, the machine having a base and a neck and the work-bench having an opening formed therein

for the removable insertion of the base of the machine, the opening being adapted to leave a groove intermediate the periphery thereof and the base of the machine when inserted, the bobbin winder having a base positioned adjacent the outer end of the neck of the machine and substantially perpendicular to the longitudinal center line of the work-bench, the tool box comprising upstanding front and back members and upstanding end members, means for securing together the abutted ends of said members, a bottom member disposed along the bottom edges of said front and back and end members, said bottom member protruding beyond said back member and coacting with the base of the bobbin winder, at least a portion of one of said end members being of arcuate form and adapted to be fitted around the neck of the machine when the protruding portion of said bottom member 15 is in abutted relationship with the base of the bobbin winder, means for dividing the interior of the box into a plurality of compartments, means coacting with the groove for removably securing the box to the work-bench, and a cover member for said box.

2. A tool box according to claim 1 in which the means for dividing the interior of the box into a plurality of compartments comprises four upstanding partitions disposed in spaced parallel arrangement intermediate the front and back members, the partition most proximate to the end member of arcuate form terminating interiorly of the box, and a fifth upstanding partition disposed on the end member of arcuate form and extended toward said partition most proximate to the end member of arcuate form.

3. A tool box according to claim 1 in which the means coacting with the groove for removably securing the box to the work-bench comprises 40 two spaced parallel projections disposed on the outer surface of the front member and extended forwardly thereof, said projections having aligned openings formed therethrough, a rod longitudinally adjustable in said openings, said rod having an opening formed therethrough intermediate the ends thereof, said opening being adapted to be aligned with the groove intermediate the periphery of the opening in the work-bench and the base of the machine, and a fastener coacting with the groove removably disposed through the opening in said rod.

4. A tool box according to claim 1 in which the cover member comprises a top member, front and back and end members downwardly depending from said top member, means for securing said members along the abutted edges thereof, said front and back and end members being slidably fitted over the outer surface portions of the corresponding members of the box, and a tray removably disposed in said cover member, the tray comprising at least a floor member, means for removably securing said floor member in said cover member, and tool holding means for said floor member.

THERESA FUHSE.
